UNITED STATES PATENT OFFICE.

GEORGE EDWARD BELLISS AND ALFRED MORCOM, OF BIRMINGHAM,
ENGLAND.

PUMP FOR COMPRESSING AIR OR GASES.

SPECIFICATION forming part of Letters Patent No. 519,225, dated May 1, 1894.

Application filed August 1, 1893. Serial No. 482,112. (No model.) Patented in England February 16, 1885, No. 2,123, and February 2, 1892, No. 1,992.

To all whom it may concern:

Be it known that we, GEORGE EDWARD BELLISS and ALFRED MORCOM, subjects of the Queen of Great Britain, residing at Birmingham, in the county of Warwick, England, have invented certain new and useful Improvements in Pumps for Compressing Air or Gases; and we do hereby declare the following to be a full, clear, and exact description of the invention, such as will enable others skilled in the art to which it appertains to make and use the same.

A patent for this invention has been obtained in Great Britain, No. 1,992, dated February 2, 1892, and features of this invention have been patented to us in Great Britain, No. 2,123, dated February 16, 1885.

The object of our invention is to produce a convenient and effective two stage compressing pump capable of operating at high pressures and with considerable frequency of reciprocation while simple in construction and readily accessible for examination and adjustment.

Our invention consists in the combination of low and high pressure single acting compressing cylinders arranged concentrically with tandem pistons compressing on opposing sides together with special water jacketing and cooling arrangements.

Referring to the accompanying sheet of drawings—Figures 1 and 2 represent vertical sections, taken in planes at right angles to one another, of a two stage pump for compressing air or gases, the parts of the said pump being constructed, combined, and worked according to our invention; the said two stage compressing pump having combined with it a water pump for pumping cooling water into the tank of the said compressing pump as hereinafter particularly explained.

The same letters of reference indicate the same parts in both figures.

A is the larger pump cylinder or chamber open at top when atmospheric air is to be compressed, but closed and put into communication with the store of or the source of gas to be compressed; B is the piston working in the said cylinder A and provided with the valve and passage at C. Surrounding the

sides and bottom of the larger pump-cylinder is a tank D containing cooling water and also the coils of pipes E and F, through which coils the compressed air or gas is cooled as it passes through them.

G is the smaller pump cylinder arranged above and concentric with the larger pump cylinder A; H is the piston or plunger working in the said smaller cylinder G. The two pistons or plungers B and H are connected by the same reciprocating piston rod J worked in any convenient way.

The bottom of the small pump cylinder G is connected to the top of the larger cylinder A and with the coils in the tank D in the following manner; K is a pipe opening into the bottom of the cylinder A and provided with an ordinary non-return valve L. This pipe K rising upward, is connected with the coil E in the tank D and the end of the coil is connected with the outside pipe M which opens by the horizontal pipe N into the top of the small pump cylinder G which has a non-return valve P and a valve Q opening into the vertical pipe R connected with the smaller coil F in the tank D. The outer end of the smaller coil F is connected with a vertical delivery pipe by which the compressed and cooled air or gas is delivered from the pump.

The action of the pump is as follows:—On the larger piston B making its upstroke, air or gas from the upper part of the cylinder A passes through the valve at C in the said piston to the space between the said piston and bottom of the cylinder A, and on the piston B making its downstroke, the air or gas is compressed and opening the non-return valve L passes by the pipe K to the lower coil E in the water tank D, for cooling the compressed air or gas. The compressed air or gas after circulating through the coil E passes by the pipes M and N to the top of the smaller cylinder G, and enters the said smaller cylinder G on the downstroke of the piston H. On the smaller piston or plunger H making its upstroke, the compressed air which has been delivered between it and the top of the said smaller cylinder is further compressed by, and pumped out of the said cylinder G, which doubly compressed air or gas opening the non-

return valve Q passes by the pipe R to the coil F in the tank D, by which coil it is cooled and is delivered by the delivery pipe from the pump. The course of the compressed air 5 or gas through the pump and cooling appliances is indicated by the full lined arrows in the drawings.

For the purpose of pumping cooling water through the tank D, and for cooling sufficiently both low and high pressure pistons, we adopt the following arrangement of parts: The bottom of the smaller cylinder G is used 10 as a water pump and is in communication by means of the passage U with the chamber V 15 of the water supply. Above the passage U is a second passage W with a valve X opening up between them. This second passage W is connected by the annular passage Y, chamber Y² and passage Y³ with the water tank D. 20 As the plunger H of the small cylinder rises in the said cylinder for effecting the second compressing operation, water is drawn into the lower part of the said cylinder, which water on the return stroke of the plunger is 25 pumped through the passages described and represented, into the tank D. The course of the water from the supply chamber V into the lower part of the pump cylinder G and from thence to the water tank D is indicated by 30 the dotted arrows in the drawings. The low pressure piston rod has a lantern brass a to allow the water of the water jacket to come into contact with the low pressure rod.

By our invention a compact and efficient 35 arrangement of a double stage air or gas compressing pump together with self contained appliances for effectually cooling the compressed air or gas is obtained.

The use of the lower part of the high pressure cylinder as a water pump has the great 40 advantage of causing the high pressure piston and the interior of the high pressure cylinder to work at all times with water contact and lubrication. The piston packing leather 45 is thus kept in admirable condition because of the low temperature of the piston, notwithstanding the high temperature of the compressed or high pressure air or gas. The high pressure cylinder is by our arrangement 50 brought in contact with water both on the internal and external surfaces.

The valve x²⁰ shown in the left hand side of 55 the large piston is a relief safety valve for the low pressure cylinder to allow the discharge of any excess pressure either due to water or to the blocking or stopping of the proper outlet valve. The valve x³⁰ in the left hand side of the upper cylinder head is for the same purpose as regards the high pressure cylin-

der, and the valve x⁴⁰ at the right in the upper end of the water tank D, is also a relief valve to prevent over pressure in the water jacket or casing.

Having now particularly described and ascertained the nature of our said invention and in what manner the same is to be performed, we declare that what we claim is—

1. In a gas or air compressor, the low and high pressure cylinders A G, the pistons B H therein, the air conduit leading directly from one end only of the low pressure cylinder to the high pressure cylinder whereby the air will be forced from the cylinder at one stroke, the cooling tank and passages and the inlet for the water connecting with one of the cylinders whereby the water will be forced through the cooling passage and tank, substantially as described.

2. In a gas or air compressor, the low and high pressure cylinders, A G, the piston B in the low pressure cylinder having a valve for the passage of air from one end of the cylinder to the other, the conduit leading from the discharge end of the low pressure cylinder to the high pressure cylinder, the air conduit leading from the high pressure cylinder, the cooling tank and the water passage leading thereto from one of the cylinders, substantially as described.

3. In combination in a gas or air compressor, the high and low pressure cylinders, the pistons therein, the air conduit from the low to the high pressure cylinder, the air conduit from the high pressure cylinder comprising the coil, the cooling tank in which said coil is located surrounding the low pressure cylinder and the water channel connected with the cooling tank and through which the water is forced by the operation of the compressor, substantially as described.

4. In combination, the low and high pressure cylinders, the pistons therein, the air conduit from the low to the high pressure cylinders, the water chamber W around the high pressure cylinder, the inlet channel U for the water leading to the high pressure chamber, the valve X opening from the inlet conduit into the chamber W and the water chamber about the low pressure cylinder connected with the water chamber W, substantially as described.

In testimony whereof we affix our signatures in presence of two witnesses.

GEORGE EDWARD BELLISS.
ALFRED MORCOM.

In presence of—

WILLIAM EVANS,
ALBERT PARKER.
